COMBINED TRANSPARENCY PROJECTOR, REAR VISION PROJECTION SCREEN, MAGNETIC TAPE DECK AND STAND THEREFOR

James J. Bicknell and George W. Bicknell, Marshall, Mich., assignors, by mesne assignments, to Audio Visual Instruction Devices, Inc., Marshall, Mich., a corporation of Michigan

Filed Jan. 27, 1967, Ser. No. 5,593

Term of patent 14 years

(Cl. D61—1)

FIG. 1

FIG. 2

FIG. 3

FIGURE 1 is a perspective view showing the front, one end, and the top of a combined transparency projector, rear vision projection screen, magnetic tape deck and stand therefor embodying our ornamental design.

FIGURE 2 is a top view.

FIGURE 3 is a perspective view similar to FIGURE 1, but showing the back, the opposite end, and the top, the tape deck being omitted for convenience in illustration.

We claim:

The ornamental design for a combined transparency projector, rear vision projection screen, magnetic tape deck and stand therefor, substantially as shown and described.
